CLAIM

The ornamental design for a guide for distributing comminuted material, as shown and described.

DESCRIPTION

FIG. 1 is an unfolded plan view of a guide for distributing comminuted material showing my new design;
FIG. 2 is a front elevational view thereof;
FIG. 3 is a top plan view thereof;
FIG. 4 is a bottom plan view thereof;
FIG. 5 is a left side elevational view thereof; the right side elevational view being a mirror image thereof; and,
FIG. 6 is a rear elevational view thereof.
The broken lines represent fold lines.
